DUST INHIBITING WATCH CROWN

Joseph Waldman, Maplewood, N. J., assignor to
 Joseph Waldman & Sons, Irvington, N. J., a
 firm

Application February 5, 1949, Serial No. 74,780

1 Claim. (Cl. 58—90)

1

This invention relates to improvements in watch crowns, and has reference, more particularly, to the provision of means in combination with a watch crown which serves to inhibit the entrance of dust through the watch crown stem admission opening of a watch case with which the watch crown is operatively assembled.

The invention has for an object to provide, in combination with a watch crown, a novel construction of dust inhibiting means of such form and relation to the watch crown and to the watch case with which the crown is assembled as to impose a plurality of barriers against entrance of dust past the watch crown and through the crown stem admission opening of the watch case, when the crown occupies its normal main spring winding position relative to the watch case; means being provided to maintain the dust inhibiting means in non-separable assembled relation to the crown; and means being also provided for maintaining the dust inhibiting means in barrier forming relation to the watch case and its crown stem admission opening.

An illustrative embodiment of the invention is shown in the accompanying drawings, in which:

Fig. 1 is a transverse vertical sectional view of a watch crown provided with the dust inhibiting means of this invention, said crown being shown in the normal position occupied thereby for both main spring windings and during running of the watch; Fig. 2 is a similar view, but showing the crown pulled out to connect it with the hand setting mechanism of the watch; Fig. 3 is a horizontal sectional view, taken on line 3—3 in Fig. 1; and Fig. 4 is a bottom plan view of the watch crown and dust inhibiting means assembly.

Similar characters of reference are employed in the above described views, to indicate corresponding parts.

Referring to the drawings, the reference character 10 indicates a suitably shaped crown body having a downwardly projecting, axially extending shank 11. Said shank 11 is provided with an internally screw-threaded axially aligned socket 12 which enters thereinto from its bottom free end, and into which is adapted to be screwed a winding and setting stem (not shown), whereby the crown may be utilized to manipulate said stem, under proper conditions, for watch winding and setting purposes. The crown body 10 is provided with a downwardly open annular recess or chamber 13 about and concentric to the shank 11.

The reference character 14 indicates an annular barrier element having a central opening 15

which is sized to fit and slidably pass the shank 11 of the crown 10 when the barrier element is entered in the recess or chamber 13 of said crown. The barrier element 14 is provided with an external side wall 16, and is so sized diametrically that said side wall 16 thereof will snugly fit but freely slidably engage the internal side wall 17 of the recess or chamber 13 in the crown, when said barrier element is entered into the latter. The barrier element 14 is provided with a flat bottom 18 which is adapted to abut the external surface of a watch case wall 19, when the crown is operatively related to the watch case.

Connected with the barrier element 14, preferably as an integral part thereof, so as to depend axially from its bottom 18, is an annular barrier sleeve 20 which is disposed concentric to the axis of the crown 10 and its shank 11. Said barrier sleeve 20 possesses an external diameter which sizes the same to enter the stem admission opening 21 with which the wall 19 of the watch case is provided, and said barrier sleeve is of a length substantially corresponding to the thickness of said watch case wall 19. The internal diameter of the barrier sleeve 20 exceeds the external diameter of the shank 11 of crown 10, whereby to provide an intermediate annular space 22 which terminates at its upper end at the bottom of the barrier element 14, thus providing the latter with an internal stop shoulder 23. Formed on and at the free end of the shank 11 of the crown is an external annular stop bead 24, which, by engagement with the stop shoulder 23, both limits outward movement of the crown 10 relative to the barrier element 14, and also serves to retain these parts together in unitary assemblage.

Entering into the central portion of the barrier element 14 from the top thereof is a countersunk annular seating socket 25 which surrounds and is concentric to the shank 11 of the crown. Mounted about said shank 11 between the crown 10 and the barrier element 14 is a helical compression spring 26, the lower end of which is footed within the seating socket 25 of said barrier element. Said spring 26 exerts a down thrusting tensional pressure upon the barrier element 14 which operates to hold the latter constantly abutted against the watch case wall 19, no matter what the relative position of the crown 10 may be, i. e. both when the crown is pulled out to watch setting position as well as when inwardly moved to normal watch winding and running position.

When the watch crown is disposed in the in-

wardly moved normal position, which it occupies during running of the watch and for use in main spring winding, the most direct path of dust and dirt infiltration to the stem admission opening 21 of the watch case is externally of the crown, i. e. between the bottom of the crown and the watch case wall 19. When the crown is equipped with the dust inhibiting means of this invention, the barrier element 14 obstructs such external path of inward dust movement, since the spring 26 thrusts down said barrier element and maintains it in constant close abutment against the area of the watch case wall which surrounds said stem admission opening. Inward movement of dust and dirt is further inhibited by the barrier sleeve 20 which enters and is engaged in the stem admission opening 21. Since the external surface of the barrier sleeve 20 is right angular to the bottom surface 18 of the barrier element 14, any infiltrating movement of dust and dirt between the watch case and these parts is therefore by way of a circuitous path which the angularly related surfaces of these parts define, thus further increasing the obstruction to inward movement of dust and dirt with added inhibiting effect.

In the aforesaid inwardly moved normal position of the watch crown, another but indirect path of dust and dirt infiltration is internally of the crown, i. e. through the hollow interior of the latter. Since, however, the external side wall 16 of the barrier element 14 closely fits and abuts the external side wall 17 of the recess or chamber 13 of the crown, such path of indirect infiltrating movement of dust and dirt is also obstructed by the barrier element 14. To provide an additional barrier against inward movement of dust and dirt through said indirect path by way of the interior of the crown, the compression spring 26 is so dimensioned that, when said spring is contracted by inward movement of the crown to the aforesaid normal position thereof, the convolutions of the spring will be closed together one upon another, thus interposing a further obstruction against inward movement of dust and dirt by way of the crown interior to the stem admission opening 21 of the watch case wall 19. By reason of the relatively spaced apart locations of the side wall 16 of the barrier element 14 and the spring 26, any infiltrating movement of dust and dirt by way of said internal path must also follow a circuitous course which further increases obstruction to inward movement thereof.

From the above description thereof it will be evident that this invention provides, in combination with a watch crown, a novel construction of dust inhibiting means which is char-

acterized by the facts that it interposes a plurality of barriers to infiltrating movement of dust and dirt, around and through the crown, at several different points, and additionally compels any such movement to follow circuitous paths which further obstruct the movement with increased inhibiting effect.

Having now described my invention, I claim:

A dust inhibiting watch crown comprising a crown body having a downwardly directed axial shank to which a winding and setting stem is to be connected, said crown body having a downwardly open recess concentric to the shank, a barrier element around the shank to fit within the recess of the crown body and with which said crown body is slidably engaged, the barrier element having a flat bottom to abut a watch case around its stem admission opening, an integral sleeve dependent from the barrier element to snugly fit within the stem admission opening of the watch case, said sleeve being of greater internal diameter than the external diameter of said shank to provide annular space therebetween, the barrier element having an internal annular stop shoulder overhanging the upper end of said space, an external stop bead at the free end of the shank adapted to be slidably moved upwardly within said space into engagement with the stop shoulder whereby to limit outward movement of the crown body relative to the barrier element, a compression spring intermediate the crown body and the barrier element operative to maintain the latter in constant abutting contact with the watch case, said barrier element having a seating socket in its top portion for reception of the compression spring, and said spring being of helical form and of such pitch that its convolutions close together when the crown body is inwardly moved to a normal position relative to the watch case, whereby to provide additional dust barrier protection.
